UNITED STATES PATENT OFFICE

HARLAN W. YENDES, OF DAYTON, OHIO

DESIGN FOR A VENDING MACHINE CABINET

Application filed February 14, 1933. Serial No. 47,214. Term of patent 7 years.

To all whom it may concern:

Be it known that I, HARLAN W. YENDES, a citizen of the United States, residing in the city of Dayton, in the county of Montgomery and State of Ohio, have invented a new, original, and ornamental Design for a Vending Machine Cabinet, of which the following is a specification, reference being had to the accompanying drawing, forming part hereof.

The figure is a perspective view of a vending machine cabinet showing my new design.

I claim:

The ornamental design for a vending machine cabinet, as shown.

HARLAN W. YENDES.
